APPARATUS FOR WASHING AUTOMOBILES
George E. Damrow, Los Angeles, Calif., assignor to The
Ni-Arb Co., Inc., El Monte, Calif., a corporation of
California

Filed Oct. 16, 1961, Ser. No. 145,213
7 Claims. (Cl. 239—135)

This invention relates to an apparatus for washing automobiles, which apparatus provides a variable content jet stream for washing action. While the invention is broadly applicable for its purpose, it has special utility for installations at gasoline service stations.

Service station operators have spare time which can be used for washing cars if a suitable apparatus for this purpose is available. The apparatus should require only a single operator and should be so efficient that the time required for washing a car is comparable to the time ordinarily required for carrying out the operation for refueling an automobile, along with the usual oil check, 15 battery check and windshield service. In addition, the apparatus should be of simple durable construction, should not require any special skill, and should be ready for use without notice and without standby cost.

This invention meets these requirements by providing a hand-operated gun for producing a high velocity jet stream and by providing a system of tanks and piping connected to the gun for varying the character of the jet stream through a cycle of operations. For example, the jet stream may initially comprise a mixture of solvent and water propelled at high velocity by compressed air. Then the jet stream may be changed to a mixture of soap and water propelled at high velocity by compressed air. Finally the jet stream may be changed to clear water for rinsing the car. A feature of the invention is that the water or water mixture may be heated for any or all of these operations.

The hand-operated gun has a liquid inlet, a compressed air inlet, a chamber or passage for mixing the air and liquid, a nozzle for discharging the jet stream, and manual valve means for control of the jet stream. The versatility of the hand gun with respect to the content of the jet stream is provided by the associated piping and tank arrangement.

A pressurized water supply is connected to the liquid inlet of the hand gun by a first passage means and, in the present embodiment of the invention, softened water is used with provision for heating the water when desired. Both a solvent tank and a liquid soap tank are connected to the first passage means to permit either grease-cutting solvent or soap or both to be mixed with the water at the operator's choice.

A source of compressed air is connected to the air inlet of the hand gun by a second passage means and a feature of the invention is that the second passage means is connected both to the solvent tank and to the soap tank. This arrangement permits the compressed air to be used for creating pressure in the two tanks to force their contents into the water stream in the first passage means.

A further feature of the invention is the application of the venturi principle for the introduction of the solvent and the liquid soap into the stream of water. For this purpose two venturi throats are provided in the first passage means and two nozzles are directed downstream into

2

the two venturi throats, the two nozzles being connected respectively to the solvent tank and the liquid soap tank.

The features and advantages of the invention may be understood from the following description considered with the accompanying drawing.

In the drawing, which is to be regarded as merely illustrative:

FIG. 1 is a somewhat diagrammatic elevational view of the apparatus; and

FIG. 2 is a fragmentary view partly in side elevation and partly in section showing the construction of a venturi arrangement that is employed for introducing the solvent and the liquid soap into the stream of water that is supplied to the hand-operated gun.

FIG. 1 shows a hand-operated gun, generally designated by numeral 10, which is of a well-known construction and is distributed by Ni-Arb Co., Inc. in El Monte, California. The hand gun 10 has an inlet 12 to be supplied with water under pressure and has a second inlet 14 to be supplied with compressed air. The flow of the water and air through the gun is controlled by a pair of corresponding valves 15 and 16 which discharge into a pair of corresponding tubes 18 and 20. The two tubes 18 and 20 lead to a mixing chamber 22 which supplies the intermixed fluid to a nozzle 24. The hand gun has a pistol grip 25 and an associated handle 26 which is adapted to open the two valves 15 and 16 simultaneously.

Water is supplied to the hand gun 10 by a pipe 28 which is connected to a suitable pressurized source such as the usual domestic water supply. The pipe 28 may be directly connected to the water inlet 12 of the hand gun but in the arrangement shown is connected through a valve 30 to an inlet 32 at the upper end of a water softener tank 34. The lower outlet port 35 of the water softener tank is connected through a valve 36 to a drain pipe 38 and is also connected to what may be termed a first passage means for supplying the softened water to the hand gun 10. As shown in FIG. 1, this first passage means may comprise a pipe 40 and a hose 41, the pipe being provided with a check valve 42 and a cut off valve 44. The hose 41 connects the pipe 40 to the water inlet 12 of the hand gun.

The illustrated embodiment of the invention provides means to heat the water stream that flows through the pipe 40 whenever such heating is desired by the operator. For this purpose an electric heater 45 is incorporated into the pipe 40, the heater being energized by a pair of leads 46. A feature of the invention is that this heater also serves as a mixing chamber.

In the arrangement shown in the drawing, a second tank 48 to contain liquid soap is mounted on legs 50 adjacent the water softener tank 34 and a third tank 52 to contain a supply of solvent is mounted on legs 54 adjacent the liquid soap tank 48. The liquid soap tank has an upper port 55 which is connected to fill a pipe 56 that is provided with a cut-off valve 58. In like manner the solvent tank 52 is provided with an upper port 60 to which is connected a fill pipe 62 having a cut-off valve 64.

The liquid soap tank 48 has a bottom outlet 65 which is connected by an upwardly extending pipe 66 to the previously mentioned water pipe 40. The upwardly extending pipe 66 may be provided with a check valve 68 and a cut-off valve 70. In the same manner the solvent tank 52 has a bottom outlet 72 that is connected to the

water pipe 40 by means of an upwardly extending pipe 74, the pipe 74 being provided with a check valve 75 and a cut-off valve 76.

A feature of this embodiment of the invention is that each of the two pipes 66 and 74 connects with a corresponding venturi arrangement in the pipe 40. As shown in FIG. 2 which shows structure at the upper end of the pipe 66, each of the venturi arrangements includes a venturi tube or nozzle 78 which points downstream inside the pipe 40 into a venturi throat 80. The venturi nozzle 78 is shown as mounted in a bushing 32 in the upper end of the pipe 66 and the venturi throat 80 is a pipe end 84 which is of reduced internal diameter with the passage of the pipe end further reduced by the associated nozzle 78. In a well known manner the local increase in velocity of flow through the pipeline 40 created by the venturi throat 80 results in a reduction of pressure which creates a pressure differential along the pipe 66 to promote flow of fluid from the pipe 66 through the nozzle 78 into the pipeline 40.

Air is supplied to the inlet 14 of the hand gun 10 through a second passage means comprising a pipeline 85 and a hose 86, the pipeline being connected to a suitable source of compressed air. As heretofore stated, a feature of the invention is the concept of connecting the compressed air pipe 85 to the two tanks 48 and 52 to create pressure therein for urging liquid soap and solvent into the water pipeline 40.

In the construction shown in the drawing, the compressed air pipe 85 is connected through a cut-off valve 88 to a pipe 90 and the end of the pipe 90 is provided with a second cut-off valve 92 which may be open to the atmosphere for a purging operation when desired. A pipe 94 branches from the pipe 90 between the two valves 88 and 92 to connect with the fill pipe 56 of the liquid soap tank 48. In like manner a second pipe 95 branches from the pipe 90 to the fill pipe 62 of the solvent tank 52.

The manner in which the invention serves its purpose may be readily understood from the foregoing description. With all of the pipe connections made to complete the installation of the apparatus, the valve 58 is opened temporarily for introducing liquid soap into the tank 48 and the valve 64 is opened temporarily for the introduction of solvent into the tank 52. Any suitable liquid soap may be employed. The solvent may be a mixture including a detergent, the mixture being of a character for effectiveness in loosening and removing grease and oil spots. During these filling operations the cut-off valve 88 is closed to isolate the supply of compressed air from the two tanks 48 and 52. After the filling operations are completed, the valve 88 is opened to admit compressed air to the upper ports of the two tanks 48 and 52. The valve 88 may then be closed to leave a charge of compressed air in each of the two tanks, or, if desired, the valve may be left opened to maintain both tanks under maximum air pressure.

With the both the liquid soap valve 78 and the solvent valve 76 initially closed, the valve 76 is opened for the first operation which consists of applying solvent to the automobile that is to be washed. The operator then uses the hand gun 10 under control of the valve handle 26 to discharge a high velocity stream of water and solvent onto the automobile. In preparation for the next step the solvent valve 76 is closed and the liquid soap valve 78 is opened. The operator then uses the hand gun 10 to direct a high velocity stream of soap and water onto the automobile to wash off the grease and solvent. The operator may take time also to clean out the radiator grill with the jet stream. A feature of the invention is that the engine of the automobile as well as the body of the automobile may be cleaned by these two operations.

In preparation for the next step both the liquid soap valve 78 as well as the solvent valve 76 are closed to permit clear water to be supplied to the hand gun 10. The electric heater 45 may be energized to heat the water and

then the hand gun 10 is manipulated to rinse off the automobile body with clear warm water.

It usually takes about three minutes for the solvent to act and the car body may be processed completely in about seven minutes. If the engine and radiator are also processed, the complete operation requires no more than fifteen minutes. Since the hand gun 10 is relatively long and since the jet stream is discharged at high velocity, the operator can stand back from the automobile and thus avoid getting wet. The operation may be interrupted at any time when desirable, for example, to wait on a second customer.

My description in specific detail of the selected embodiment of the invention will suggest various changes, substitutions and other departures from my disclosure within the spirit and scope of the appended claims.

I claim:

1. In an apparatus for washing automobiles, the combination of: a hand gun having a nozzle for projecting a stream of mixed fluid, an air inlet in communication with the nozzle, a liquid inlet in communication with the nozzle, and a manual valve means; a water softener tank having an outlet and having an inlet for connection to a pressurized water supply; a first passage means for conducting a stream of the softened water from said outlet of the tank to said liquid inlet of the hand gun; a liquid soap tank having an outlet connected to said passage means for adding soap to said stream of water; a solvent tank having an outlet connected to said passage means for adding solvent to said stream of water; and a second passage means for connection to a supply of compressed air, said second passage means being connected to said liquid soap tank and to said solvent tank to force the soap and solvent into said stream of water and being also connected to said air inlet of the hand gun to mix air with said stream of water in the hand gun.

2. A combination as set forth in claim 1 which includes a heater for heating the fluid in said first passage means downstream from the liquid soap and solvent tanks.

3. In an apparatus for washing automobiles, the combination of: a hand gun having an air inlet, a liquid inlet, and a nozzle in communication with both inlets; a first passage means connected to said liquid inlet of the gun for connecting the gun with a pressurized water supply; a liquid soap tank having an upper port and having a lower outlet port connected to said passage means; a solvent tank having an upper port and having a lower outlet port connected to said passage means; and a second passage means connected to said air inlet of the gun for connecting the gun to a supply of compressed air, said second passage means being connected to said upper ports of the liquid soap tank and the solvent tank to force liquid soap and solvent into said first passage means.

4. In an apparatus for washing automobiles, the combination of: a hand gun having an air inlet, a liquid inlet, and a nozzle in communication with both inlets; a first passage means connected to said liquid inlet of the gun for connecting the gun with a pressurized water supply; a liquid soap tank having an upper port and a lower outlet; a solvent tank having an upper port and a lower outlet; two nozzles directed downstream in said first passage means and connected to said outlets of the liquid soap tank and the solvent tank respectively; and a second passage means connected to said air inlet of the gun for connecting the gun to a supply of compressed air, said second passage means being connected to said upper ports of the liquid soap tank and solvent tank to force liquid soap and solvent into said first passage means.

5. In an apparatus for washing automobiles, the combination of: a hand gun having an air inlet, a liquid inlet, and a nozzle in communication with both inlets; a first passage means connected to said liquid inlet of the gun for connecting the gun with a pressurized water supply, said passage means having two venturi throats at points

spaced apart longitudinally thereof; a liquid soap tank having an upper port and a lower outlet; a solvent tank having an upper port and a lower outlet; two nozzles directed downstream into said two venturi throats respectively, said nozzles being connected to said outlets of the liquid soap tank and solvent tank respectively; and a second passage means connected to said air inlet of the gun for connecting the gun to a supply of compressed air, said second passage means being connected to said upper ports of the liquid soap tank and solvent tank, respectively, to force liquid soap and solvent into said first passage means.

6. A combination as set forth in claim 5 which includes a heater for heating the fluid in said first passage means

downstream from the liquid soap tank and the solvent tank.

7. A combination as set forth in claim 6 in which said heater is also a mixer for intermixing fluids in said first passage means.
